DESIGN FOR A BEACH SLIPPER

Stephen Babinehak, New York, N. Y.

Application March 23, 1940, Serial No. 91,191

Term of patent 7 years

To all whom it may concern:

Be it known that I, Stephen Babinehak, a citizen of the United States and residing at New York city, in the county of New York and State of New York, have invented a new, original, and ornamental Design for a Beach Slipper, of which the following is a specification, reference being had to the accompanying drawing, forming part thereof, and in which

Fig. 1 is a top view of a beach slipper showing my new design,

Fig. 2 is a side view,

Fig. 3 is a bottom view,

Fig. 4 is a perspective view upon a somewhat smaller scale as compared to Figs. 1 to 3, show-

ing the forward portion of the beach slipper in flexed position.

The leading distinctive feature of the design of the present application resides in the provision of an intermediate or middle portion separated from and positioned between toe and heel portions, over which, without attachment thereto, arches crossing straps, giving the middle portion an appearance of being suspended between the toe and instep portions of the sandal.

I claim:

The ornamental design for a beach slipper, substantially as shown and described.

STEPHEN BABINCHAK.
